CLAIM

The ornamental design for a necktie as shown and described.

DESCRIPTION

FIG. 1 is a front perspective view of a necktie showing my new design;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof; and,

FIG. 8 is a rear perspective view thereof.

The various shaded colors of surface shading applied to the surfaces of the necktie represent a contrast in appearance and form part of the claimed design.

1 Claim, 8 Drawing Sheets
